UNITED STATES PATENT OFFICE.

ENPEI NISHINA, OF TOKYO-FU, JAPAN, ASSIGNOR OF ONE-HALF TO KAZO YAMAGUCHI,
OF KITA-KU, OSAKA, JAPAN.

METHOD OF MAKING A FLAT FIBROUS WEB.

Application filed December 1, 1921. Serial No. 519,265.

To all whom it may concern:

Be it known that I, ENPEI NISHINA, a subject of the Emperor of Japan, residing at No. 833 Oaza-nakameguro, Meguro-mura, 5 Ebara-gun, Tokyo-fu, Japan, have invented a certain new and useful Improvement in a Method of Making a Flat Fibrous Web, of which the following is a specification.

The present invention relates to a method 10 of causing fibrous substance mixed with any suitable adhesive material to adhere and solidify by projecting it by suitable means out of spouts upon the surface of a slowly moving wire gauze, felt, cloth or such like 15 fabric, thus the fibrous substance forming a continuous film; and the object thereof is to obtain a simple method of solidifying the pulp of fibrous substance so as to form a flat fibrous web.

20 The invention is clearly illustrated in the accompanying drawing which shows in elevation and partly in section an apparatus for carrying out the method.

Referring more particularly to the drawing there is provided a tank 1 which contains 25 pulp suspended in a liquid containing any suitable sizing material. The liquid in the tank 1 flows down through a pipe 2 and a discharge spout 3, provided with an adjustable valve 4 by which flow of the fluid is 30 regulated. Just below the discharge spout 3, there is a nozzle 5 through which is blown 35 out air coming from a pipe 6 and having a pressure of not less than 2,000 lbs., say 5,000 lbs., per square inch. The compressed air 40 will atomize the pulp containing liquid flowing from the spout 3 and will project it on the surface of an endless belt 9. That part of the belt at which the pulp is to be projected is supported by a roller 8 which is 45 covered by a sucking device 7 which is connected with a sucking pump (not shown) through a leading pipe (16). The sucking pump sucks off the air and the remaining 50 liquid which is forced through the endless belt. The paper sheet thus formed on the surface of the endless belt is then taken over another endless belt 11 which travels over rollers 12 and is dried by a drying drum 55 13. There is over the nozzle a cover 14 and a fan 15 which blows away the air which has been deflected by the belt.

The following is an example of the manner of carrying this invention into practice.

55 Upon the surface of wire gauze vertically

stretched and slowly moved by any suitable device, project pasty fibrous pulp previously mixed with sizing material and pigment out of spouts under a strong pressure. Then, 60 the pulp will adhere to the wire gauze, and at the same time the superfluous water contained in the substance will be squeezed out by the force with which it is projected. After drying or half drying, the substance 65 is taken off from the wire gauze and is flattened and calendered with rolls so as to form a continuous and smooth film or pasteboard.

The projected pulp, instead of being 70 rolled, may be pressed into moulds in wet state to produce various articles of papier maché; or sometimes felt, cotton cloth or the like may be used as the ground on which fibrous substance is projected, and the fibrous substance may be left adhering thereto, the 75 fabric used as the ground then serving as a reinforcing material.

Besides the above described applications, the present invention may be applied to the manufacture of artificial leather, belt, 80 insulating belt, linoleum or other floor cloths, substitutes for wood, or various other materials for industrial purposes, only in these cases care must be taken to select kinds of fibrous substances and binding materials 85 suitable for the different purposes according to the case.

The chief feature of the present invention thus consists in projecting fibrous substance 90 out of spouts under a strong pressure upon the surface of some slow moving wire gauze, felt, cotton cloth or the like, and in causing the substance to adhere to the surface thereof, forming a continuous film.

The specific structure for forming a web 95 is covered in my copending application Ser. No. 576,114, filed July 19, 1922, now Patent No. 1,519,696 granted Dec. 16, 1924.

Claims.

1. A method of making a flat fibrous web, 100 consisting in treating a fibrous substance with a sizing material and projecting the mixture toward a porous surface, forcing air under high pressure against the projected mixture to atomize the mixture and deposit 105 the same on the porous surface, and simultaneously moving the surface as the mixture is projected thereon to effect the formation of an even film.

2. A method of making a flat fibrous web 110

consisting in projecting a mixture of fibrous substance and sizing material under high pressure to atomize the same and cause it to adhere to a porous surface, simultaneously moving the surface to effect an even coating or film during the projecting of the material, removing the film thus formed from the surface and finally performing finishing operations thereon, substantially as and for the purposes set forth.

3. A method of making a flat fibrous web consisting in treating a fibrous material with a sizing material and projecting the same under high pressure upon a porous surface so that the solid portions will adhere to the surface and the liquid portions will be carried through the surface, simultaneously moving the surface during the projecting of the mixture to cause an even film to be formed on the surface, removing the film

thus formed, and finally performing finishing operations on the film, substantially as and for the purposes set forth.

4. A method of making a flat fibrous web consisting in treating a fibrous material with a sizing material and projecting the mixture under high pressure upon a surface of porous material to cause the fibrous material to adhere to the porous material and the excess liquid portions of the mixture to be carried through the porous material, simultaneously moving the porous material during the projecting of the fibrous mixture to effect the formation of an even film on the porous material, performing finishing operations upon the film and porous material, substantially as and for the purposes set forth.

In testimony whereof I have affixed my signature.

ENPEI NISHINA.
